MAP IN BOOK FORM

Nils Olof Bergquist, Alsten, Sweden

Application October 1, 1934, Serial No. 746,452
In Sweden October 5, 1933

6 Claims. (Cl. 283—35)

This invention refers to such printed matters as maps, diagrams, schedules, tables, drawings, etc. which are generally too large to be handy when they are unfolded, and unsurveyable when they 5 are divided into sections of smaller size and collected in book form.

As maps are the most important group of articles, to which the invention is applicable, the following description and illustrations will refer only 10 to maps. The corresponding application to other matters is obvious and selfexplanatory.

As large maps are not handy to use when touring, walking, hiking, etc., it has already been proposed to cut a map into sections along horizontal, 15 that is West-East, and vertical, that is North-South, lines and to bind these sections into a book so that sections correlated in a horizontal direction i. e. perpendicular to the back of the book will form a set of consecutive pages following one another in order from West to East while the sets of pages corresponding to the various horizontal rows of sections follow in order from 20 North to South.

Pages which are correlated in westerly or easterly direction are easily found by turning over 25 the pages forwardly or backwardly. In order to facilitate the finding of pages correlated in northerly or southerly direction the pages are numbered and the respective numbers of correlated pages are quoted at the margin at the top and/or 30 bottom of the page. It is thus possible to ascertain the page number of a correlated page and to turn to this page. Usually the atlas is supplied with a survey or leading map in the front of the book, which serves to facilitate finding a desired 35 section. In some cases there has been provided a visual index, fully visible only from the leading map. In such an arrangement only one of the correlated sections is visible and seizable from the 40 section exposed whereas the other section is only available after turning back to the leading map.

According to my invention the leaves are provided at their edges with tabs forming finger grips so arranged and combined with markings or 45 signs for indicating the finger grips of adjacent sections correlated in a direction parallel with the back of the book, that each section, having two adjacent sections in the direction last mentioned, will have a marked finger grip on each side of the back of the book by means of which each 50 of said adjacent sections is directly accessible from the section exposed.

Fig. 1 shows a modification of the invention.

Fig. 2 shows a second modified form of the invention.

Figs. 3, 4 and 5 disclose a third modification of the invention.

In the accompanying drawings which illustrate three embodiments of the invention, Figure 1 shows a form in which each leaf is printed on both sides, the pages 2 and 3 being open at once, as are also pages 4 and 5 and so on. Pages 3 and 4 represent the opposite sides of the same leaf, front and back, and have therefore the same tab; so also pages 5 and 6, 7 and 8, and so on.

If the user has to follow a road which passes the border of a section in westerly or easterly direction, passing the left or right border respectively, it is only necessary to turn to the next page or to the preceding page, for instance, in travelling from the town A on page 10 to the town B on 15 page 11 and further to the town E on page 12.

When leaving a section in a northerly or southerly direction, for instance, when travelling from B on page 11 to C on page 17, there is first to be 20 observed the location of the tab at the edge of page 11. Thereafter there is found the next leaf having a tab at the same location which is then exposed by putting a finger on the tab and turning over the intervening leaves. When following 25 a road to the North, for instance, from E on page 12 to F on page 6, the corresponding preceding page having a tab at the same location will be similarly accessible after lifting the tab of page 12. Thus, in this case the tabs of the section exposed will form themselves the markings above 30 referred to.

In order to facilitate travel in this direction, North to South, there may be indicated, by means of an arrow or some other sign, what page is to be turned over in order to arrive at the page sought. When travelling from B on page 11 to C on page 17, it will be observed that the arrow on 35 page 11 is located at the middle of the edge. The next page with a tab at the middle of the edge is page 15 which should be turned over, thus exposing page 17.

It is obvious that instead of providing a separate section of the map on each page as in the embodiment described, each pair of pages which are open at once may contain a single uninterrupted section covering both pages and folded along the back of the book.

Figure 2 shows a modification of the kind last mentioned. The sections are numbered 1 to 16. 50 In this case the number of tab locations has been chosen greater than the number of sections or pair of pages in one horizontal strip, West-East. Thus one strip has been divided into four sections, but the tabs are located at six different places.

At the edges of the pages there are provided signs, such as "S" and "N" (South and North, respectively), or it may be some other sign or indication, which leads in some way to the finger grip 5 or tab to be used in exposing the correlated section. Thus, if the user desires to travel in northerly or southerly direction, it is only necessary to grip the tab opposite the sign in question, to the right when going south and to the left 10 when going north, to retain the relative page and to turn over the intermediate pages.

In order to obtain sufficient space for each finger grip it is usually required to use two or more series of tabs the tabs of each series being 15 distributed along the whole length of one edge of the pages. The tab division may vary but it should be seen from the description of the two embodiments described that in using a number of tabs in each series which is larger than the 20 number of page sections or pairs of pages, or the largest number of sections respectively, in one horizontal strip, the tabs of adjacent sections will always be directly accessible from the section exposed, whereas in case the number of tabs is equal 25 to the number of sections or pair of pages of a horizontal strip, as in Figure 1, the tabs of sections correlated in a vertical direction will cover each other. The system of tab division used in Figure 2 may, of course, be applied to the embodiment shown in Figure 1, in which case there 30 may be for instance four tabs in each series, i. e. one more than the number of sections or pair of sections in a horizontal strip.

Figures 3, 4 and 5 show a modification in which 35 the tabs are provided at the upper and lower edges of the pages. The book in this case contains nine sections forming together a map cut into three horizontal strips. In the upper picture of Figure 3 the book is opened to show the 40 first section, in the middle picture to show the ninth section and in the lower picture to show the fifth section. The numbers of the various sections are marked on the corresponding upper and lower tabs for facilitating the finding of any 45 particular section after a glance at a leading map. As there is only one series of tabs at the upper and at the lower edge respectively the numbers of all sections will be seen from each section exposed as well as from the leading map. The 50 correlated north section will be reached by means of the upper tabs and the south section by means of the lower tabs. By using signs such as N and S placed opposite the tabs of the correlated sections the section wanted can be found and exposed at once by putting the finger on the tab so marked and turning over the intervening pages.

Obviously the invention may be applied to books of other contents consisting of sections which form together a larger area, over which 55 one may want to follow certain lines in different directions.

I claim:—

1. A book comprising in combination, a plurality of pages which display sections of a large sheet obtained by dividing the sheet along parallel lines in two directions perpendicular to each other, a tab projecting from the edge portion of the majority of pages, the tabs of adjoining pages overlapping each other only partly and a mark on each of said pages indicating an adjoining section, said mark being positioned on the edge portion of such page and at a level with the tab 10 on the page displaying the adjoining section. 5

2. The book of claim 1, in which the marks on pages to the left of the spine of the book point to tabs on preceding pages, the marks on pages to the right of the spine to tabs on succeeding pages. 15

3. The book of claim 1, in which the pages display sections of a map and consecutive pages display sections adjoining each other in the order of one of the four directions of the rose, the pages displaying such adjoining portions forming a group and groups of sections adjacent in a direction of the rose perpendicular to the first direction being arranged in consecutive order, the mark on a page of each group being positioned at a level with the tab projecting from the page 20 of the adjoining group displaying the perpendicular adjoining section. 25

4. A book comprising in combination, a plurality of pages which display sections of a large sheet obtained by dividing the sheet along parallel lines in two directions perpendicular to each other, tabs projecting from the respective edge portions of the majority of pages, the individual tabs of any exposed section leaving the tabs of all adjoining sections freely visible, and a sign 35 on each page indicating the tabs of the adjoining sections. 30

5. A book comprising in combination, a plurality of pages which display sections of a large sheet obtained by dividing the sheet along parallel lines in two directions perpendicular to each other, tabs projecting from the respective edge portions of the majority of pages, the individual tabs of any exposed section leaving the tabs of all adjoining sections freely visible, a distinguishing mark on each tab, and a sign on each page indicating the tabs of the adjoining sections. 40 45

6. A book comprising in combination, a plurality of pages which display sections of a large sheet obtained by dividing the sheet along parallel lines in two directions perpendicular to each other, tabs projecting from the respective edge portions of the majority of pages, the individual tabs of any exposed section leaving the tabs of all adjoining sections freely visible, a distinguishing mark on each tab, and a sign on each page indicating the tabs of the adjoining sections, said sign being positioned on the edge portion of such page and at a level with the tab on the page displaying the adjoining sections. 50 55 60
